UNITED STATES PATENT OFFICE

111,133

DESIGN FOR A SPOON OR OTHER ARTICLE OF FLATWARE

Elizabeth Alberta Brenner, Youngstown, Ohio

Application June 22, 1938, Serial No. 77,992

Term of patent 14 years

To all whom it may concern:

Be it known that I, Elizabeth Alberta Brenner, a citizen of the United States, a resident of Youngstown, county of Mahoning, and State of Ohio, have invented a new, original, and ornamental Design for a Spoon or Other Article of Flatware, of which the following is a specification, reference being had to the accompanying drawing, forming a part hereof, in which:

Fig. 1 is a front elevational view of a spoon or other article of flatware embodying my new design;

Fig. 2 a side elevational view thereof;

Fig. 3 a rear elevational view thereof; and

Fig. 4 an enlarged cross-sectional view taken on the line 4—4 of Fig. 1.

I claim:

The ornamental design for a spoon or other article of flatware, substantially as shown.

ELIZABETH ALBERTA BRENNER.
